DESIGN FOR A BOTTLE

Manuel A. Frank, Philadelphia, Pa., assignor of one-sixth to Max Frank, one-sixth to Anna Frank, one-sixth to Mary Frank, one-sixth to Perry B. Frank, and one-sixth to Sidney Frank, all of Philadelphia, Pa.

Application September 15, 1938, Serial No. 79,923

Term of patent 7 years

To whom it may concern:

Be it known that I, Manuel A. Frank, a citizen of the United States, residing at 4919 Parkside Ave., city of Philadelphia, in the county of Philadelphia and State of Pennsylvania, have invented a new, original, and ornamental Design for Bottles, of which the following is a specification, reference being had to the accompanying drawing, forming part thereof.

The figure is a side view in elevation of a bottle, showing my new design. The bottle is round and has substantially the same appearance on the opposite side.

I claim:

The ornamental design for a bottle, as shown and described.

MANUEL A. FRANK.
